UNITED STATES PATENT OFFICE.

BRODEHURST ELSEY AND CHARLES F. ZWICK, OF INDIANAPOLIS, AND HOMER C. LAWSON, OF RICHMOND, INDIANA.

GLOVE.

1,333,395.

Specification of Letters Patent.

Patented Mar. 9, 1920.

Application filed February 23, 1917. Serial No. 150,562.

To all whom it may concern:

Be it known that we, BRODEHURST ELSEY and CHARLES F. ZWICK and HOMER C. LAWSON, citizens of the United States, and residents of Indianapolis and Richmond, counties of Marion and Wayne and State of Indiana, have invented a certain new and useful Glove; and we do hereby declare that the following is a full, clear, and exact description thereof, reference being had to the accompanying drawings, in which like letters refer to like parts.

This invention relates to a glove and has as its object the construction or manufacture of a working glove which will be sturdy and durable and may still be cheaply made.

The chief feature of the invention is the construction of a glove such as above referred to, by making a glove entirely of cloth and then facing it with leather on the palm and a portion of the fingers, in the sides thereof and in the crotch between the fingers and on the backs of the fingers at and near the ends thereof so that when the glove is used for picking up coal, picking and handling corn or holding reins, the back of the finger tips and the surfaces in the crotch of the fingers will be protected and at the same time be so constructed as to be cheaply made from small pieces of leather which are practically useless, having accumulated from the cutting of the general line of gloves.

The full nature of the invention will be understood from the accompanying drawings and the following description and claims:

In the drawings, Figure 1 is a plan view of the palm of the glove. Fig. 2 is a plan view of the back of the glove. Fig. 3 is a plan view of the leather portion adapted to be used on the palm. Fig. 4 is a plan view of the leather portion adapted to be secured to the thumb. Fig. 5 is a plan view of the cloth portion of the palm of the glove. Figs. 6, 7, 8, 9 and 10 are plan views of the leather pieces secured to the fingers of the glove. Fig. 11 is a plan view of the cloth thumb portion. Figs. 12, 13 and 14 are plan views of the cloth portion of the backs of the fingers and hand. Fig. 15 is a plan view of the back of a portion of two fingers of the glove spread apart.

In the drawings there is shown a glove having a palm 10, a back 11 and gauntlet 12.

Stitched to the gauntlet there is a cloth 55 palm portion 13 with a leather palm portion 14 secured to the outer side thereof. A cloth thumb portion 15 and leather portion 16 are then stitched together to the gauntlet and palm portion, said leather portion 16 covering only that part of the cloth portion as shown in Fig. 1, said leather being stitched to the outside of the portion 15 by the stitching 17. The little finger portion 18, made of cloth, is then stitched to 60 the cloth and leather palm so that it covers the back of the little finger and extends from the tip thereof to the gauntlet, as shown in Fig. 2. At the same time the leather piece 19 is secured on the outside thereof and 70 stitched in the seam joining the little finger portion to the palm portion of the glove. The cloth portion 20 is stitched to the portion 18 and to the palm so as to extend back to the gauntlet. At the tip of said 75 portion the leather pieces 21 and 22 are stitched so as to overlap and cover the greater part of the finger portion, as shown in Fig. 2. The cloth portion 23 is stitched to the portion 20 and the index finger portion 24 so as to extend back to the gauntlet. The leather pieces 21 and 25 are secured thereto so as to cover the finger portion. The leather piece 26 is stitched to the finger of the cloth portion 24. 80

The glove made as above described is practically a glove made of cloth throughout with the leather facings superimposed on the cloth, although in some parts the cloth and leather portions have their edges 85 united to the other portions together. The parts shown in Figs. 5, 11, 12, 13 and 14 when united make a complete cloth glove. The parts shown in Figs. 3, 4, 6, 7, 8, 9 and 10 are the leather facings. 90

The sides and crotches of the fingers are formed by the leather pieces 19, 21, 22, 25 and 26, the right hand cut-off ends abutting against each other and when united form the crotches and side pieces of leather extending from the side edges of the leather constituting the palm of the fingers outward and over the backs of the ends of the fingers, as shown in Fig. 2, the upper edges of said strips of leather being inclined as shown so as not to cover or come very near the second joints of the fingers and thus make the fingers of the glove very flexible. 100

95

105

at said joints, for the second joints of the fingers of the hand are covered only by the cloth.

From the foregoing description of the various parts of the glove and the manner in which they are associated together, it will be seen that the back of the fingers and the crotch which are the most vulnerable parts of a working glove, are strengthened 10 and protected by combining a plurality of small pieces which may be taken from scraps of leather, thus greatly cheapening the manufacture.

The invention claimed is:

15 1. A glove made of cloth and having a reinforcing facing thereon of leather covering the palm of the hand and fingers, and pieces of leather secured to the finger portions thereof and covering the sides and 20 crotch surfaces of the fingers and extend-

ing over the backs of the fingers toward the ends thereof so as to leave free the portions of the fingers of the glove which are adapted to cover the second joints of the fingers of the hand.

2. A glove made of cloth, a reinforcing leather facing thereon consisting of a piece covering the palm and inner surfaces of the fingers, and dart shaped pieces secured to the edges of the fingers of said palm leather covering and covering the insides and crotches of the fingers and cut so as to meet each other on the backs of the fingers near the ends thereof, substantially as set forth.

In witness whereof we have hereunto af- 35 fixed our signatures.

BRODEHURST ELSEY.
CHARLES F. ZWICK.
HOMER C. LAWSON.
